UNITED STATES PATENT OFFICE.

JOHN J. TURNER, OF NEW YORK, N. Y.

DESIGN FOR A WASHER.

SPECIFICATION forming part of Design No. 31,081, dated June 27, 1899.

Application filed June 2, 1899. Serial No. 719,150. Term of patent 7 years.

To all whom it may concern:

Be it known that I, JOHN J. TURNER, a citizen of the United States, residing at the city of New York, borough of Manhattan, in the 5 county and State of New York, have invented and produced a new and original Design for a Washer, of which the following is a specification, reference being had to the accompanying drawings, forming a part thereof, in 10 which—

Figure 1 represents a side elevation of a washer embodying the features of my design, and Fig. 2 is a plan view of the washer.

The leading feature of the design consists 15 of an inverted funnel-shaped body A, an in-

verted conical cap B, and spouts C, extending from the sides of the cap.

The minor features of the design consist in the openings a, that appear in the lower portion of the body A, and the tapering contour 20 of the spouts C, together with the downward inclination of said spouts.

I claim—

The design for the washer herein shown and described.

JOHN J. TURNER.
